● *To all whom it may concern:*

Be it known that I, WALLACE D. SIMMONS, a citizen of the United States, residing at the city of St. Louis, in the State of Missouri, have invented a new, original, and ornamental Design for a Medal or Emblem, of which the following is such a full, clear, and exact description as will enable any one skilled in the art to which it appertains to make the same, reference being had to the accompanying drawings, forming part of this specification.

My invention is shown in the drawing, which is an elevation showing the design of the medal or emblem.

As therein shown, the principal features of my design are the representations of the heads of an elephant and of a donkey placed side by side and above these a representation of an equestrian statue of a knight, the words "Saint Louis" appearing in raised letters immediately below the statue.

I claim—

The ornamental design for a medal or emblem as shown and described.
